UNITED STATES PATENT OFFICE

WALTER H. WHEELER, JR., OF STAMFORD, JACOB W. OGDEN, OF SPRINGDALE, AND FRANCIS J. ROUAN, OF EAST PORT CHESTER, CONNECTICUT, ASSIGNORS TO PITNEY-BOWES POSTAGE METER CO., OF STAMFORD, CONNECTICUT, A CORPORATION OF DELAWARE

PAPER CUTTING DEVICE

Application filed February 20, 1931. Serial No. 517,352.

This application is in part a division of our application filed April 26, 1930, Serial No. 447,534 (Case 7727) for attachment for postage meter machines, and is filed in accordance with official requirement for division.

The present invention is a novel means for cutting a strip or web of paper or other thin material and is useful either alone, or in connection with various kinds of machines where-
10 in such a strip or web is to be severed.

In the accompanying drawings we have illus-
15 trated two practical embodiments of the invention and will explain the same with refer-
ence thereto as illustrative thereof; but we
do not consider the invention limited in scope
to the specific constructions shown. In the
claims the essential features of the invention
20 and the novel features of construction and
novel combinations of parts for which pro-
tection is desired are set forth.

In said drawings:

Fig. 1 is a front view of the cutter. Fig. 2 is a plan view. Fig. 3 is a rear view and Fig. 4 an end view of such cutter. Fig. 5 is a trans-
25 verse section showing the cutter open for the
passage of a strip or web. Fig. 6 is a similar
view showing the position of the parts upon
severing the web or strip. Fig. 7 is a front
view of a modification of the cutter. Fig. 8
30 is a longitudinal horizontal section on line
8—8, Fig. 7. Fig. 9 is a transverse section of
such cutter showing the parts in position for
passage of a web before severing. Fig. 10 is a
similar view showing the position of the
35 parts just after severing the web. Fig. 11 is
a side view of the cutter detached.

As shown in Figs. 1 to 6 the cutter com-
40 prises a body 10 which is longitudinally bored
and screw threaded as indicated, but the rear
part of the body is recessed longitudinally as
at 10a the recess extending into the threaded
portion, as shown in Figs. 2, 5.

Entered in body 10 and engaging the
45 threaded portion thereof is a cutter formed of
a threaded cutter rod 11 which has part of its
threaded portion corresponding to the recess
10a cut away as at 11a. The body 10 has a
slot 10b opposite the cut away portion
50 through which slot passes the web or strip W
which is to be severed. The slot 10b is pref-

erably longitudinally inclined at an obtuse an-
gle to the rod (Figs. 1 and 3) to give a shear
to the cutting edge. The cut away portion 11a
of the rod (Figs. 1 and 11) leaves a flat ex-
tending the whole length of the cut away por-
tion 10a of the body so that the strip or web
W may be readily threaded between these cut
away portions when rod 11 is in the position
indicated in Figs. 1 to 5.

The cutter rod may be rocked or turned by
any suitable means and when said rod is
rocked its finely serrated edge 11c (produced
by the cut threads of the rod, Fig. 2) will
pinch the paper against the serrated edge 10c
of the body (produced by the cut threads at
the upper side of the slot 10b, Fig. 1) and
these fine serrations will cleanly sever the web
or strip and the slight relative longitudinal
movement of the rod and body due to the
threads facilitates the severance of the web or
strip of material inserted therebetween.

The rod may be operated manually or me-
chanically by any suitable means; and, when
applied to an attachment such as shown in our
aforesaid application Serial No. 447,534 by
75 the means indicated in Figs. 4-6. In such
case a member having two arms 12 and 12a is
attached to the projecting end of rod 11. Such
member can be fitted on the square end
of the cutter rod and secured by a screw 12s
80 and its arms 12 and 12a are adapted to be en-
gaged by a reciprocating bar 8; said bar hav-
ing a slot 8g in its end which as the bar moves
to the right first engages the arm 12a and
rocks the member and cutter rod 11 clock-
wise; such movement engaging arm 12 with
the slot 8g in the bar 8. This rocking move-
ment of the cutter rod 11a causes its serrated
edge 11c to cooperate with the serrated edge
10c and sever the strip W. Slide bar 8 may
90 be moved to the left by a spring (not shown)
and slot 8g then engaging arm 12 rocks rod 11
anti-clockwise and returns it to the position
indicated in Figs. 4 and 5.

In the construction shown in Figs. 7-10 the
95 screw member 11s is fixed and the sleeve nut
or casing member 10s is rotatable. In this
construction the said members being cut away
as indicated, similarly to the parts 10 and 11
in Figs. 1-6. The threaded rod 11s is fixedly
100

mounted, and as shown is secured in lugs 13a on a bracket 13 which may be fastened to a suitable base or to the machine with which the cutter is to be used. The sleeve nut 10s is rotatably mounted upon the screw 11s, and the arm 12a may be attached to this casing, and operated as above described whereby at each reciprocation of the bar 8 the sleeve nut 10s is rocked to sever the web W as indicated in Figs. 9 and 10.

Obviously the invention is not dependent upon the particular means for oscillating the cutter rod 11 or the casing member 10s as they can be operated by various means, as will be obvious to a mechanic, either manually or by proper connections with the operative mechanism of the machine on which the cutter is used. The particular means for rocking the movable member of the cutter not being an essential feature of the present invention.

In a cutter having members with intermeshing serrated edges, similar to the screw and nut type here illustrated, even if the cutting edges become dull, the paper strip cannot be drawn in between them as in the case of dull, or poorly set shears or scissors; as the paper has not sufficient tensile strength to stand the distortion necessary to allow it to follow the sinuous line of cleavage between the serrated edges of the rod and body; and therefore the strip will be cleanly severed when the members are sharp, or cleanly torn apart when they are dull.

35 We claim:

1. A paper cutting device consisting of a threaded member having a longitudinal recess in its threaded portion the cut threads providing a serrated edge on said recess adapted to sever the paper.

2. A paper cutting device consisting of a body having a slot with a serrated edge at one side, and a rod extending longitudinally of the slot also having a serrated edge, the paper being free to pass between the serrated edges of the body and rod in the normal position of the rod, and means for relatively rotating the body and rod to sever the paper.

3. A paper cutting device consisting of a slotted body having a serrated edge, and a rod extending longitudinally of the slot having a recess in its threaded portion the cut threads providing a serrated edge on said recess, said slot and recess permitting free passage of the web or strip when the parts are in normal position; and means for relatively rocking the body and rod to sever the web by the coaction of the serrated edges.

4. A paper cutting device comprising a threaded body and a threaded rod each having a longitudinal recess in its threaded portion, such recesses permitting a web or strip to freely pass therebetween in one position of the parts, and the web being severed by relatively rotating the body and rod.

5. A paper cutting device consisting of a body having a slot with a serrated edge, and a threaded rod extending longitudinally of the slot having a recess coincident with the slot the cut threads imparting a serrated edge to the recess, said parts in normal position permitting free passage of the paper through the slot, and means for relatively rocking the body and rod to sever the paper by the action of the serrated edges. 70 75

6. A paper cutting device consisting of a body having a slot with a serrated edge at one side, a threaded rod extending longitudinally of the slot and having a recess coincident with the slot, and cut threads of the rod providing a serrated edge adapted to cooperate with the serrated edge of the slot; the web or strip being free to pass between the serrated edges of the body and rod in one position thereof; and means for relatively rotating the body and rod to sever the web. 80 85

7. A paper cutting device comprising a threaded body and a threaded rod each having a longitudinal recess in its threaded portion, which recess when their flat sides are 90 approximately parallel permit the paper to freely pass therebetween; the paper being severed by relatively rotating the body and rod.

8. A paper cutting device comprising an internally threaded body and an externally threaded rod engaging the body, each having a longitudinal recess in its threaded portion, the cut threads forming serrated edges on such recess, said recesses when their flat sides are approximately parallel permitting free passage of the paper therebetween, and said body and rod when relatively rotated severing the paper by the coaction of their serrated edges. 100

9. A paper cutting device consisting of an internally threaded body having a longitudinal recess in one side of its threaded portion, and an externally threaded rod extending longitudinally of the body and having a longitudinal recess coincident with that of the body, the said recesses permitting a web or strip to pass between the serrated edges of the body and rod in their normal positions, and means for relatively rotating the body and rod to sever the paper. 110 115

10. A paper cutting device consisting of an internally threaded body having a longitudinal slot the cut threads serrating the inner edge of the slot; and a threaded rod extending longitudinally of the slot and having a recess coincident with the slot the cut threads serrating the edge of the recess, the web or strip being free to pass between the serrated edges of the body and rod in one position thereof; and means for rotating the rod in the body to cause the serrated edges to sever the web. 120 125

11. A paper cutting device consisting of an internally threaded tubular body having a 130

longitudinal slot, the cut threads imparting a serrated edge to the edge of the slot; and a threaded rod extending longitudinally through the body and having a recess coincident with the slot the cut threads of the rod imparting a serrated edge to the rod recess adapted to cooperate with the serrated edge of the slot, the web or strip being free to pass between the serrated edges of the body and rod in one position thereof, the body being mounted upon the rod, and means for rotating the body on the rod to sever the web.
